IMPULSE DISTRIBUTOR

Clyde J. Fitch, Endwell, N. Y., assignor to International Business Machines Corporation, New York, N. Y., a corporation of New York

Application December 28, 1940, Serial No. 372,110

2 Claims. (Cl. 178—53.1)

This invention relates to an improved impulse distributor particularly adaptable for use in printing telegraph systems.

In the present improved distributor, an induction motor of the stall duty type is provided, and through resilient connecting means tends continuously to advance an escapement wheel which is directly connected to suitable circuit controlling means. In order to effect release of the escapement wheel at the desired times, a control magnet and associated armature are provided, the latter having stop means cooperating with the said wheel for releasing it intermittently upon successive energizations of the said magnet.

An object of the present invention resides in the provision of an improved impulse distributor wherein a predetermined torque is applied constantly to an escapement element, the release of which is under direct control of a vibratory member.

Another object of the present invention resides in the provision of an improved impulse distributor having motor driving means continuously tending to advance an escapement wheel, and electromagnetic control means for releasing the said wheel upon successive energizations thereof.

Another object of the present invention resides in the provision of an improved impulse distributor having motor driving means continuously tending to advance an escapement wheel through the agency of a resilient coupling, and magnet control means for releasing the said wheel upon successive energizations thereof.

Other objects of the invention will be pointed out in the following description and claims and illustrated in the accompanying drawing, which disclose, by way of example, the principle of the invention and the best mode, which has been contemplated, of applying that principle.

In the drawing:

Fig. 1 is a plan view of the improved impulse distributor.

Fig. 2 is a side elevation view of the said distributor, showing in section the resilient coupling of the driving and driven shafts.

Fig. 3 is a detail view of the escapement wheel.

Fig. 4 is a detail view of the armature assembly.

Fig. 5 is a detail view of one of the cam segments secured to the distributor shaft.

Fig. 6 is a detail view showing the cooperation of the escapement member with the escapement wheel.

With reference now to the figures, the improved impulse distributor is shown to comprise

suitable motor driving means 10, such as a low torque induction motor which is wound for stall duty purposes, mounted on a supporting member 11, and having suitable coupling means for effecting rotation of the distributor shaft 12, the latter being journaled in the spaced supporting frames 13.

A plurality of circuit controlling means, such as the spaced conducting cam segments 14, are secured to the distributor shaft, which cam segments are effective to engage the related conducting brushes 15, at predetermined times, during the rotation of shaft 12. In Fig. 5, one of the conducting cam segments are shown in detail. The said brushes are suitably supported by an insulating member 16, which in turn is secured to the supporting member 11. It is understood, of course, that the said conducting cam segments and related brushes merely are one illustration of circuit controlling means. In place of the said brushes, spaced contact spring arms may be substituted, which can be operated, to close or open the related contacts, by individual related cams secured to the distributor shaft, at different times during the rotation of the said shaft. This latter type of circuit controlling means is well known in the telegraphy art.

An escapement wheel 17 (shown in detail in Fig. 3) having, for example, four equally spaced stop fingers 18 is also secured to the distributor shaft 12. Cooperating with the escapement wheel are a pair of offset stops 19 and 20 which are formed as an integral part of the armature 21 of magnet 22. The said armature assembly, upon energization and deenergization of the magnet 20, is arranged to be partially rotated about the point indicated by reference character 23 as its pivot.

With reference now to Fig. 2, it is seen, that, in the normal position of the armature assembly, the stop 19 is positioned in the path of one of the stop fingers 18 of the escapement wheel; and, upon energization of magnet 22 to partially rotate the assembly in a counterclockwise direction, the stop 19 is displaced out of the path of the stop fingers of the escapement wheel, thereby permitting the latter to be released, and rotated a predetermined angular distance. However, upon displacement of the armature assembly, the stop 20 is positioned in the path of the stop fingers of the escapement wheel, thereby preventing further advancement of the said wheel. The armature assembly is restored to the normal position shown by means of spring 24, upon de-

energization of magnet 22, thereby displacing the stop 20 out of the path of the stop fingers, and permitting the wheel to be advanced until one of the stop fingers again engages the stop 19.

The configurations of the stop fingers of the escapement wheel and the stops of the armature assembly are such, that upon displacement of the latter, either to the left or right, as viewed in Fig. 2, the escapement wheel is released to effect rotation of the distributor shaft one eighth of a revolution, for each displacement of the stops. Thus, it is understood, that the distributor shaft is advanced, in equal predetermined steps, upon successive energizations and deenergizations of the magnet 22. The described armature assembly is referred to as a vibratory escapement member.

In practice, it is preferred to control the successive energizations of the magnet 20 by means of a suitable oscillatory means, such as an electronic oscillation generator of the type fully described in the copending application Serial No. 370,675, filed Dec. 18, 1940. Also, it is preferred to energize continuously the winding 25 of the motor driving means, in order to tend to rotate continuously the motor or driving shaft 26.

A sleeve member 27 is secured to the driving shaft and elongated sufficiently to extend over the free end of the distributor shaft 12. Resilient coupling means is provided in the form of a coil spring 28, which is disposed on the sleeve 27, and one end of which is connected to the sleeve, and the other end of which is connected to the escapement wheel 17.

Now, with the escapement wheel held in a fixed position by the armature assembly as shown, the motor armature and shaft are rotated to wind the spring 28 until the tension of the latter is equal to the torque applied thereto, thereby stalling the motor driving means.

From the description given, it is evident, that, upon successive energizations and deenergizations of the control magnet to position or vibrate the armature assembly from right to left, and vice versa, as viewed in Fig. 2, the escapement wheel and distributor shaft are released to permit them to be rotated, step by step, through equal angu-

lar distances. As the distributor shaft is permitted to rotate, the motor armature and shaft continue their follow up operations, thus, always maintaining the spring in a wound condition. In this manner, there is no time lag in applying the starting torque to the distributor shaft upon operation of the armature assembly.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. An impulse distributor of the character described, comprising, in combination, motor driving means having a driving shaft tending to rotate continuously, normally inoperative distributor shaft and circuit controlling means, said shafts disposed in a co-axial relation with each other, an escapement wheel fixed to one end of said distributor shaft, an elongated sleeve member secured to said driving shaft having one end thereof disposed in close proximity to the escapement wheel, coil spring means surrounding said sleeve member, one terminal of which being connected to the other end of said sleeve member and the other terminal to the escapement wheel, thereby normally tending to rotate the latter, an electromagnet, and a pivoted escapement armature assembly cooperating with said wheel for normally preventing rotation of the latter, but effective to release the said wheel for rotation upon energization of the electromagnet.

2. The invention set forth in claim 1 characterized by the fact that the said escapement wheel is provided with a plurality of equally spaced stop members for permitting rotation of the distributor shaft, step by step, through equal angular displacements upon successive energization and deenergization of said electromagnet.
